UNITED STATES PATENT OFFICE.

JOSEPH F. POND, OF CLEVELAND, OHIO.

CHIMNEY COWL AND VENTILATOR.

SPECIFICATION forming part of Letters Patent No. 290,266, dated December 18, 1883.

Application filed August 9, 1883. (No model.)

To all whom it may concern:

Be it known that I, JOSEPH F. POND, a citizen of the United States, residing at Cleveland, in the county of Cuyahoga and State of 5 Ohio, have invented certain new and useful Improvements in Chimney Cowls and Ventilators; and I do declare the following to be a full, clear, and exact description of the invention, such as will enable others skilled in the 10 art to which it appertains to make and use the same, reference being had to the accompanying drawings, and to the letters and figures of reference marked thereon, which form a part of this specification.

15 My invention relates to improvements in chimney-cowls; and the novelty consists in the construction, arrangement, and adaptation of parts, as will be more fully herein-after set forth; and specifically pointed out in 20 the claims.

The object of the invention is to produce a device which shall be inexpensive of manufacture, simple and efficient in service, of ready adjustment, and durable.

25 The invention is fully illustrated in the accompanying drawings, which form a part of this specification, and in which—

Figure 1 is a front elevation of the invention as applied to a sheet-metal pipe; Fig. 2, a vertical central section of the same, and Fig. 3 a detail. Fig. 1^a is a detached perspective view of one of the guide-plates.

Referring to the drawings, in which similar 35 letters of reference indicate like parts in all the figures, A designates the upper end of the smoke-chimney or exit-pipe, and B the body-plate of which the cowl-shield is formed. By rivets b a socket-frame, C, is secured to the main shield, and in the upper portion of 40 said frame C, between it and the shield B, is confined the step c, one point of which is slipped into a perforation, c², in the socket-frame, and the other held thereto by a screw, c', as seen in Fig. 3. The step c has a concave bearing at c³ for the reception of the pivot end of the pin d, and this pin has its 45 bearings in a double frame or spider, D, the arms d' of which are provided with holes, by means of which the said frame may be se-

cured to the pipe A. A collar, d², on the 50 pivot-pin d has a steadyng-bearing in the socket-frame C.

H designates metal plates having holes h' and a hooked portion, h. When this hooked portion h rests over the upper edge of the 55 pipe, the holes h' arbitrarily suggest the location of the cowl—that is to say, when the holes in the frame D and the plates H register, and the hooks of the plates H are engaged over the tops of the pipe, the position 60 of the cowl is decided—which will bring lower rear edge of the auxiliary shield slightly below the upper edge of the pipe—the position in which the best results are attained. Thus the plates H not only serve as guides to de- 65 note the proper adjustment and position of the cowl, but they relieve the rivet-holes of wearing and tearing strain in the pipe A, said pipe being firmly clasped between the arms d' and the plates.

G designates a drooping vane, secured to the inner under side of the cowl-body, and it is 70 designed to catch the wind and assist in turning the shield.

In devices of this kind a difficulty occurs, 75 frequently, from the fact that wind is free to pass between the rear lower edge of the shield and the pipe, and thus destroy the partial vacuum formed within the cowl. I provide against this by an auxiliary shield, F, which 80 extends vertically down from the main shield, to which it is secured, to a point below the upper edge of the pipe A and closely contiguous thereto, partially surrounding the same. This feature I deem to be of much im- 85 portance.

What I claim as new is—

1. In combination with the main shield B and socket-frame C, provided with perforation c², the step c, having concave c³, and being secured at one point by a screw, c', and the pivot-pin d, having collar d², as and for the purposes set forth.

2. In combination with the shield B, open on the side, and pipe A, the auxiliary shield F, located within the shield B, as and for the purposes set forth.

3. In combination with the spider D, hav-

ing perforated arms d' , and the shield B and pipe A, the adjusting and strengthening plates H, having perforations h' and hooks h , as and for the purposes set forth.

5 4. In combination with the shield B and socket-frame C, having aperture c^2 , the step c , having one end passed through the said socket-frame, and screw c' , as and for the purposes set forth.

In testimony whereof I affix my signature in presence of two witnesses.

JOSEPH F. POND.
